UNITED STATES PATENT OFFICE.

RANDOLPH CROMPTON AND WILLIAM E. WOODMAN, OF WORCESTER, MASSACHUSETTS;
SAID WOODMAN ASSIGNOR TO SAID CROMPTON.

MISTHREADING DEVICE FOR WEFT-REPLENISHING LOOMS.

1,408,171.

Specification of Letters Patent. Patented Feb. 28, 1922.

Application filed May 26, 1919. Serial No. 299,973.

To all whom it may concern:

Be it known that we, RANDOLPH CROMPTON and WILLIAM E. WOODMAN, both of Worcester, in the county of Worcester and Commonwealth of Massachusetts, both citizens of the United States, have invented a new and useful Improvement in a Misthreading Device for Weft-Replenishing Looms, of which the following, together with the accompanying drawings, is a specification.

Our invention relates to an improvement in misthreading devices for automatic weft replenishing looms. Automatic weft replenishing looms, as ordinarily constructed, are provided at one side with a weft replenishing mechanism, and on the opposite side with weft or filling detecting devices. When the filling in the active shuttle becomes exhausted or broken, absence of filling is indicated by the detecting device on the next detecting beat of the lay, and on the following or nondetecting beat of the lay a fresh supply of filling is inserted into the shuttle from the magazine of the weft replenishing mechanism. Various filling detecting devices have been employed to either stop the loom upon the detection of filling absence in the shuttle, or to permit the filling in the shuttle to be replenished several times before stopping the loom, since it is known that several successive hopper misthreads may be permitted without seriously impairing the quality of the cloth being woven.

The object of the present invention is to provide a novel form of filling detecting device which permits several successive misthreads to take place before stopping the loom.

Misthreading devices of the above described character as heretofore constructed, have usually comprised various instrumentalities carried on the top of the breast beam and adapted to actuate the knock-off lever of the loom upon the occurrence of one or of several misthreads. The arrangement of the moving parts of the device upon the top of the breast beam leaves them subject to accidental engagement with external objects which might result in their disarrangement or in premature stoppage of the loom, particularly since the knock-off lever is usually provided with a portion projecting above the top of the breast beam.

By our invention we propose to entirely

reorganize the arrangement of parts in a misthreading device so that the parts which are adapted to actuate the knock-off lever are located at the end of the loom and below the top of the breast beam. We further provide an arrangement of parts in which the member adapted to cause actuation of the knock-off lever is held in an inoperative position by the force of gravity, so that the chances of accidental operation thereof are reduced to a minimum.

In the accompanying drawings,

Figure 1 is a plan view of the left hand end portion of a loom showing the application of my improved misthreading device thereto.

Figure 2 is a side elevation of the parts shown in Fig. 1.

Figure 3 is a front elevation of the parts shown in Fig. 1.

Figure 4 is a sectional view along the line 4—4, Fig. 1.

Figures 5 and 6 are detail views along the line 5—5, Fig. 1, showing the parts in different operating positions.

Figure 7 is a view of a portion of the parts shown in Fig. 1, showing the position which they occupy during the normal operation of the loom.

Figure 8 is a view similar to Fig. 7, showing the position of the parts upon the detection of filling absence.

Figures 9 and 10 are fragmentary views showing the position of a portion of the parts following the detection of two successive filling absences.

Figure 11 is a view similar to Fig. 8 showing the position of the parts following the detection of three successive absences and upon actuation of the knock-off lever.

Similar reference characters refer to similar parts in the different figures.

The loom to which the improved misthreading device is attached, and in which only the left hand end portion is shown, may be of any usual preferred form. The general parts of the loom shown comprise a breast beam 1, a knock-off lever 2, a weft hammer 3, adapted for reciprocatory motion backward and forward once to every two forward beats of the lay, not shown, and a rocker shaft 4 extending longitudinally of the loom and suitably connected to the weft replenishing mechanism, all as shown in Fig. 2.

A filling or detector fork 5 is pivotally

supported at one end of a detector slide 6 that is slidably mounted in a bracket 7. As best shown in Fig. 4, the slide 6 is provided at its other end with an eye bolt 8 that is 5 adapted to receive the hooked portion 9 of a detector arm 10 carried by the rocker shaft 4. The weft hammer 3 is provided with a forked arm 11 extending beneath the detector slide 6 and provided at its end with 10 a barb 12 that is adapted to engage the tail 13 of the detector fork 5, when the detector fork is depressed upon the filling absence. When the barb 12 engages the tail 13 of the detector fork 5, as shown in Fig. 2, 15 the slide 6 is pushed forward, thereby causing the detector arm 10 to turn the rocker shaft 4 and set in operation the weft replenishing mechanism. The rocker shaft 4 is further provided with a knock-off arm 14 20 that is adapted to move toward the knock-off lever 2 when the shaft 4 is turned as described above. The motion of the arm 14 is not sufficient to move the knock-off lever 2 and thereby stop the loom until the knock-off actuator 15 is interposed between the 25 arm 14 and the lever 2, as shown in dotted lines, Fig. 2. The knock-off actuator 15 forms part of the filling detecting mechanism which will now be described.

30 The hooked portion 9 of the detector arm 10 is embraced by the bifurcated portion of a lever 16 that is pivotally connected to a link 17 carried at one end of a shaft 18 mounted on the breast beam 1. The other 35 end of the shaft 18 projects beyond the end of the breast beam 1 and carries a link 19 that is connected to a sliding pawl 20 by means of a curved lever 21. The pawl 20 is pivotally supported by a stud 22 and is 40 provided with a slot 23 so that it is capable of longitudinal movement with respect to the stud 22. A spring 24 connected between the top of the pawl 20 and the breast beam 1 tends to maintain the pawl in its upper position, with the lower end of the slot 23 in 45 engagement with the stud 22. The stud 22 is carried by a bracket 25 that is slidably mounted upon an upwardly extending rod 26, the bracket 25 being provided with a set 50 screw 27 by means of which it may be clamped in different positions with respect to the rod 26.

As best shown in Figs. 1 and 2, the actuator 15 comprises an L-shaped head 15^a and 55 is secured to an arm 28 by means of a set screw 29. The actuator 15 is provided with a slot 30 by means of which its position with respect to the arm 28 may be adjusted. The arm 28 is pivotally supported upon an actuator slide 31 by means of a pin 32, and a spring 33 disposed between projections carried by the slide 31 and the arm 28, respectively, tends to maintain the actuator head 15^a away from the knock-off lever 2. The

actuator slide 31 is adapted to move vertically upon the rod 26 and is provided on its outer face with a series of teeth 34. The slide 31 is limited in its downward movement on the rod 26 by means of a stop 35, that is capable of adjustment for a purpose 70 to be hereinafter more fully described.

The pawl 20 is biased in the direction of the teeth 34 of the slide 31 by means of a leaf spring 36 mounted on the rod 26. A second pawl 37 pivotally mounted on the 75 stud 22, as best shown in Fig. 3, is also biased toward the teeth 34 by means of a spring 38. During the normal operation of the loom the pawls 20 and 37 are held out of engagement with the teeth 34 by means 80 of a stop lever 39 that is provided at its lower end with a projection 40 extending across the faces of the pawls. The stop lever 39 is pivotally mounted on the stud 22 and is connected at its upper end to a shaft 41 by means of a link 42. The shaft 41 extends across the breast beam 1 substantially parallel to the shaft 18 and is connected at its end to a pawl stop arm 43 by means of a link 44. The stop arm 43 extends in the 90 direction of the lay and is supported at its free end in a notch 45 provided at the end of an arm 46 carried by the detector slide 6, as best shown in Fig. 1. The pivot pin 47 which connects the stop arm 43 to the link 95 44 projects beyond the link 44 and is normally located in a notch 48 provided at one end of a latch lever 49. As best shown in Figs. 1 and 5, the latch lever 49 is pivotally supported by a stud 50 on a bracket 51 carried by the breast beam 1 and is normally held against the pin 47 by means of a spring 52. The spring 52 also tends to hold the other end of the latch lever 49 in engagement with the arm 46, the end of the lever 105 being bevelled, as shown at 53, for a purpose to be hereinafter described.

During the normal operation of the loom the free end of the stop arm 43 is in the line of motion of a bunter 54 carried at the end 110 of the weft hammer 3, so that each forward stroke of the weft hammer moves the stop arm 43 away from the lay, thus maintaining the pin 47 in the notch 48 of the latch lever 49. The springs 36 and 38 acting through 115 the stop lever 39 and the shaft 41 tend to force the stop arm 43 in the direction of the lay, but as long as the pin 47 remains in the notch 48 this movement is prevented. The parts remain in the above described positions so long as the detector fork 5 does not indicate any filling absence in the bobbin.

Having described the various parts entering into my invention the operation thereof is as follows:—Assume that the lay has completed its detecting beat and that the detector fork 5 has been turned about its pivot 120 out of engagement with the barb 12 of the

weft hammer by its engagement with the filling. The parts then occupy the positions shown in Fig. 5, in which the stop arm 43 has just been struck by the bunter 54 of the weft hammer and the pin 47 is in the notch 48, thus maintaining the pawls out of engagement with the teeth 34 of the actuator slide 31.

Assume that on the next detecting beat of 10 the lay the filling fork 5 encounters no filling and consequently remains in the line of motion of the barb 12. On the next forward movement of the weft hammer 3, the barb 12 engages the tail 13 of the detector fork and carries the slide 6 forward to turn 15 the rocker shaft 4 and actuate the filling replenishing mechanism. As the slide 6 moves forward the arm 46 engages the bevelled end 53 of the latch lever 49 and moves 20 it in a clockwise direction about its pivot to the position shown in Fig. 6, whereupon the pin 47 is free to move toward the lay and thereby permit movement of the pawls toward the teeth 34. At the same time a cam 25 portion 55 provided on the stop arm 43 is engaged by the bottom of the notch 45 and the stop arm 43 is lifted upwardly out of the path of motion of the weft hammer 3, as shown in Fig. 8, thus permitting the 30 pin 47 to remain on the upper side of the notch 48. At substantially the same time as the pawl 37 engages the base of the topmost tooth 34, the sliding pawl 20 is moved downwardly by the forward movement of the detector slide 6, until the tip of the pawl 20 35 engages the edge of the topmost tooth. The pawl 20 lifts the actuator slide 31 until the pawl 37 engages the topmost tooth upon the forward movement of the detector slide 6, 40 as shown in dotted lines, from which it will be noted that the movement of the knock-off arm 14 toward the knock-off lever is not sufficient to actuate the lever.

Assuming that a second filling absence is 45 indicated by the detector fork 5, the stop arm 43 will be lifted out of the path of movement of the weft hammer by the engagement of its cam portion 55, with the bottom of the notch 45 in the arm 46, upon 50 the forward movement of the slide 6. The pin 47 then remains on the upper side of the notch 48 and the stop lever 39 permits the pawls to again engage the actuator slide 31 and move it upward a distance equal to 55 the pitch of one tooth, as shown in Fig. 9.

Upon the detection of a third successive filling absence the pawl 20 will again lift the actuator slide, as shown in Fig. 10.

Upon the detection of a fourth successive 60 filling absence, the pawl 20 will move the slide 31 upwardly until the pawl 37 engages the lowest tooth and at the same time the actuator head 15^a will be moved upwardly into the line of motion between the knock-

off arm 14 and the knock-off lever 2, as 65 shown in Fig. 11. The knock-off arm 14 will then engage the actuator head 15^a as the rocker shaft 4 is turned by the detector slide on the next forward movement of the hammer 3 and turn the actuator about its 70 pivot into engagement with the knock-off lever 2 to stop the loom.

From the above described arrangement of parts it is apparent that if the detector fork 5 fails to indicate filling absence after the 75 insertion of two or even three new fillings in the shuttle by the action of the weft replenishing mechanism, the slide 6 will not be moved and its arm 46 will allow the stop arm 43 to remain in the path of the approaching weft hammer, whereupon the weft hammer 3 will engage the stop arm 43 and return the pawls and the actuator to their normal position, as shown in Fig. 7, 80 and the loom will continue to operate, as 85 before. Consequently the knock-off lever will be actuated to stop the loom only upon the occurrence of four successive filling absences with the parts in the position shown in Fig. 2. If, however, it should be desired to stop the loom upon the occurrence of only three, two or even one filling absence, it is only necessary to loosen the bolt 90 securing the stop 35 to the rod 26 and move it upwardly a distance equal to one, two 95 or three times the pitch of the teeth 34. The stop 35 will then limit the downward movement of the slide 31 to such an extent that any one of the first three teeth 34 may be permanently held out of engagement by 100 the pawl 20. In this way, the loom can be caused to stop upon the occurrence of any predetermined number of filling absences according to the number of teeth that may 105 be engaged by the pawls.

It is also apparent that the location of the moving parts of the knock-off lever actuator at the end of the loom and below the top of the breast beam greatly reduces the possibility of accidental operation of the actuator. Furthermore, the fact that the actuator slide and the actuator are normally held in an inoperative position by the force of gravity further reduces the likelihood of 110 premature operation.

While we have shown a specific arrangement of the well known parts of a loom our invention is not limited in its application to looms of this type, but may as well be applied to any known type of loom, with such 120 modifications in the arrangement of parts as may be necessary. We desire therefore that only such limitations be imposed thereon that come within the scope of the appended claims.

We claim,

1. In a loom, a filling detector, a slide adapted to be moved upon the detection of

filling absence, a knock-off lever, and a vertically movable knock-off lever actuator adapted to be lifted step-by-step by the movements of said slide, the said actuator being held in an inoperative position with respect to said knock-off lever by the force of gravity.

2. In a loom, a filling detector, a slide adapted to be moved upon the detection of filling absence, a knock-off lever, a knock-off lever arm and a knock-off-lever actuator normally independent of the movements of said arm and adapted to be lifted into an operative position with respect to said knock-off lever and said arm by the movements of said slide, the said actuator being normally held in its inoperative position by the force of gravity.

3. In a loom, filling replenishing mechanism, a filling detector, a detector slide adapted to be moved upon the detection of filling absence to actuate the filling replenishing mechanism, a knock-off lever, a knock-off lever arm adapted to move in the direction of said lever simultaneously with the actuation of the filling replenishing mechanism, and a knock-off lever actuator adapted to be lifted step-by-step into the path of motion of said arm to actuate said lever upon the detection of the fourth successive filling absence.

4. In a loom, filling replenishing mechanism, a filling detector, a detector slide adapted to be moved upon the detection of filling absence to actuate the filling replenishing mechanism, a knock-off lever, a knock-off lever arm adapted to move in the direction of said lever simultaneously with the actuation of the filling replenishing mechanism, and a knock-off lever actuator normally independent of the movements of said arm and adapted to be lifted into the path of motion of said arm, the said actuator being normally held out of the path of motion of said arm by the force of gravity.

5. In a loom, filling replenishing mechanism, a filling detector, a detector slide adapted to be moved upon the detection of filling absence to actuate the filling replenishing mechanism, a knock-off lever, a knock-off lever arm adapted to move in the direction of said lever simultaneously with the actuation of the filling replenishing mechanism, and a knock-off lever actuator normally independent of the movements of said arm and adapted to be lifted a predetermined distance in the direction of the path of motion of said arm, upon each detection of filling absence and to be returned to its inoperative position by the force of gravity upon the detection of filling presence.

6. In a loom, filling replenishing mechanism, a filling detector, a detector slide adapted to be moved upon the detection of filling absence to actuate the filling re-

plenishing mechanism, a knock-off lever, a knock-off lever arm adapted to move in the direction of said lever simultaneously with the actuation of the filling replenishing mechanism, and a knock-off lever actuator adapted to be lifted into the path of motion of said arm, by a step-by-step movement, to actuate said lever upon the detection of several successive filling absences and to be returned to its inoperative position by the force of gravity upon the detection of filling presence.

7. In a loom, filling replenishing mechanism, a filling detector, a detector slide adapted to be moved upon the detection of filling absence to actuate the filling replenishing mechanism, a knock-off lever, a knock-off lever arm adapted to move in the direction of said lever simultaneously with the actuation of said filling replenishing mechanism, and a knock-off lever actuator adapted to be lifted step-by-step into the path of movement of said arm to actuate said lever upon the detection of several successive filling absences.

8. In a loom, filling replenishing mechanism, a filling detector, a detector slide adapted to be moved upon the detection of filling absence to actuate the filling replenishing mechanism, a knock-off lever, a knock-off lever arm adapted to move in the direction of said lever simultaneously with the actuation of said filling replenishing mechanism, and a knock-off lever actuator adapted to be lifted step-by-step into the path of movement of said arm to actuate said lever upon the detection of a predetermined number of filling absences.

9. In a loom, filling replenishment mechanism, a filling detector, a detector slide adapted to be moved upon the detection of filling absence to actuate the filling replenishment mechanism, a knock-off lever, a knock-off lever arm adapted to move in the direction of said lever simultaneously with the actuation of said filling replenishment mechanism, and a knock-off lever actuator adapted to be lifted step-by-step into the path of movement of said arm to actuate said lever upon the detection of one or more filling absences, the number of such absences being determined by the number of steps which the said actuator is permitted to take.

10. In a loom, filling replenishing mechanism, a filling detector, a detector slide adapted to be moved upon the detection of filling absence to actuate the filling replenishing mechanism, a knock-off lever, a knock-off lever arm adapted to move in the direction of said lever simultaneously with the actuation of the filling replenishing mechanism, and a knock-off lever actuator adapted to be lifted into the path of motion of said arm, by a step-by-step movement, to actuate said lever upon the detection of sev-

eral successive filling absences and to be returned to its inoperative position by the force of gravity upon the detection of filling presence, the inoperative position of said actuator being adjustable to determine the number of steps required to move it into the path of movement of said arm.

Dated this seventeenth day of May, 1919.
